CLAIM

The ornamental design for a bullet light luminaire, as shown and described.

DESCRIPTION

FIG. 1 is a front, upward perspective view of a bullet light luminaire;

FIG. 2 is a front, downward perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines in the Figures are included for the purpose of illustrating unclaimed portions of the bullet light luminaire and form no part of the claimed design.
